UNITED STATES PATENT OFFICE

2,627,755

ELECTROMAGNETIC STEPPING
MECHANISMDonald E. Hooker, Skokie, Ill., assignor to
Raymond T. Moloney, Chicago, Ill.

Application October 24, 1951, Serial No. 252,858

2 Claims. (Cl. 74—129)

1

This invention pertains to electromagnetically-actuated stepping mechanism of the pawl and ratchet class, and has as its principal object the provision of a high-speed stepping mechanism for use with devices of this class.

It is a further and more specific object to provide a stepping mechanism of the class described, which is relatively economical to make, which is simple and reliable in construction and operation, and which includes as a feature thereof several driving pawls actuated by a single solenoid and spring means to step a single ratchet disc at increased speed by reason of the driving action of all pawls at some phase of each complete operating stroke or cycle of the driving solenoid or other driving means.

A further specific object is the provision, in a device of the class described, of means including twin stepping pawls actuated in concert by a single solenoid to move relative to a ratchet wheel so that the wheel is advanced by one pawl on the initial stroke of the solenoid, and the wheel is again advanced by the other pawl on the return stroke of the solenoid, so that the rate of stepping advance of the wheel is multiplied for each operating cycle of the pawl means.

A further object is to provide a stepping mechanism which moves the ratchet wheel in a more nearly continuous motion when the pawl means is rapidly actuated.

Another object is the provision of an indexing or indicating mechanism of the pawl-and-ratchet stepping type which includes a ratchet wheel driven in consecutive steps by two co-reciprocable pawls, each of which steps the wheel once, sequentially, for each complete reciprocatory and joint travel of the two pawls, together with a sweep index arm rotatable with the wheel and lodged into uniformly spaced, successive positions of rest which are at least two steps apart about the arc of travel of said arm.

Additional objects and aspects of novelty and utility relate to details of the construction and operation of the illustrative embodiment described hereinafter in view of the annexed drawing, in which:

Fig. 1 is a front elevation of the novel stepping mechanism;

Fig. 2 is a top plan view of the device shown in Fig. 1;

Fig. 3 is a fragmentary rear elevation of the stepping mechanism disclosing a rotary signal driven thereby;

Fig. 4 is a fragmentary front elevational detail showing the driving pawls in the advancing phase of the power stroke.

2

Referring to Fig. 1, the stepping mechanism is shown mounted on a base plate 10 adapted to stand upright on base flange 11.

Driving or actuating means for the mechanism 5 includes an electromagnetic solenoid or coil 12 having a plunger 13 reciprocable therein, mounted on the plate by means of brackets 14, and adapted to be energized by connections with conductors 15 in any desired control circuit (not shown).

The member to be stepped or driven is a ratchet wheel 18 rotatably mounted on a stud shaft 19 journaled in the base plate.

Dual-acting stepping means includes a pair of 15 pawls 20 and 21 each pivotally connected at 20A and 21A with a corresponding link 20B or 21B, said links each being pivotally mounted on the base plate on pin means 23, the two links also having their respective inner ends pivotally connected at 24 to the solenoid plunger 13, such that reciprocable movements of said plunger impart simultaneous rocking motions to the links, with a consequent simultaneous reciprocation of the two driving pawls 20 and 21.

25 The pawls are yieldingly urged toward each other by a linking spring 25 stretched between pins on each pawl, so that the offset nose portions 20X and 21X thereof are normally urged into the ratchet teeth 18X.

30 A normalizing spring 26 has one end anchored on a pin 27 in the base plate, and its other end attached to one of the pawl-link pivot connections 21A, and acts to rock the link 21B clockwise (Fig. 1), so that the solenoid plunger 13 is normally withdrawn thereby, and the two pawls are disposed in a normal starting position relative to the ratchet wheel 18.

35 It is important to observe in Fig. 1 that the pitch of the ratchet teeth presented to the pawls is reversed by reason of the engagement of the pawls on opposite sides of the pivotal center of the wheel.

40 As a result of the aforesaid opposite pitching, it will be clear that when the pawls advance from the normal position shown in Fig. 1 to the advanced position of Fig. 4 (with solenoid plunger 13 attracted) the pawl 21 will have advanced the ratchet disc a distance of one tooth by pushing against the particular tooth 18XY, whereas the other pawl 20 will have slipped past the particular tooth 18XZ.

45 It is also important to observe that in the latter slipping action of pawl 20 over tooth 18XZ, the said tooth was moved backward toward the pawl 50 20 and its nose 20X, concurrently with the advancing motion of the pawl 20 toward said back-

ward moving tooth 18XA, since the other pawl 21 is at this same time driving the wheel counter-clockwise, so that by the time the pawl 21 has finished its driving stroke the companion pawl 20 is also fully advanced into a critical position to drivingly engage the tooth 18XZ upon return travel of the pawls.

Actually, it is preferred that the pawl 20 shall relatively overtravel the tooth 18XZ by a pre-determined amount, as indicated by the arrows marked O. T. in Fig. 4. This assures several important actions, namely: complete advance of the ratchet wheel on the advancing movement of the first pawl 21; a positive advance of the second pawl 20 past the tooth 18XZ later to be driven thereby; a time interval for positive completion of the first power stroke and step and positioning of the second pawl for its power stroke; and finally, a momentary no-load condition for the second pawl 20 during which it can overcome its reverse-travel inertia and gain some momentum in the return direction before loading by driving engagement with tooth 18XZ on the return travel, it being noted that this return travel and working power is effected by the normalizing spring 26, and it is desirable that this spring shall be strong enough to do the necessary work on the return stroke, on one hand, and yet not overly strong to load the system unnecessarily on the initial advancing stroke of pawl 21.

The stroke of the pawl system is limited in the return direction by a stop in the form of set screw 28 (Fig. 1) mounted in a bracket 27 on the base plate, and positioned to be engaged by part of the pawl-link pivotal connection at 20A. In the opposite direction, it is satisfactory to have the inward stopping position of plunger 13 in coil 12 effect the limiting travel for the forward or initial advancing stroke of the pawls.

Such a stepping mechanism is useful in many applications, for example, in connection with rotary switches; to actuate signals or a score-register or totalizer device, such as shown in Figs. 2 and 3.

As depicted in Fig. 2, the shaft 19 has fixed thereon a metal arm 30 having attached to its end a socket 31 carrying a small sweep lamp 32. The socket shell 31 may be grounded to said arm and have its remaining terminal connected by a conductor 33 to the metal annulus 34 of a commutator ring fixed between two larger annular insulating rings 35. A spring wiper contact rides between the discs 35 on ring 34 and completes an energizing circuit (not shown) for the movable lamp.

The stepping mechanism steps the arm 30 to position the lamp 32 before circularly arranged indicia (Fig. 3) 37 arranged on an opaque panel 38 situated before the aforesaid sweep lamps. The panel 38 has been simplified to display only a few illustrative number indications 37, but it will be apparent that the stroke of the pawls and the number and spacing of the ratchet teeth 18X may be modified to yield a greater or lesser range of steps, and gearing may be interposed (not shown) between the drive shaft 19 and the arm 30, or other driven means, to extend the stepping range as desired.

By selecting a solenoid plunger structure and pawl mechanism of suitable minimized weight, the travel of the arm 30 may be made so rapid as to appear continuous rather than discontinuous. On the other hand, by holding the coil 12 energized, the arm 30, and hence the lamp or other device 32 can be stopped intermediate any

two normal positions, as for example between the indications 100 and 200, etc., in such instance, giving no signal through the opaque panel 38.

The described construction clearly doubles the stepping speed of the ratchet system since each complete reciprocation or stroking of the solenoid plunger 13 effects two steps of the wheel 18; and it will also be apparent that rapid reciprocation of the plunger thereby effects a more nearly continuous rotative motion of the wheel, while at the same time undesirable loading by the spring 26 and the relatively idle pawl 20 is minimized during the working stroke of the other pawl 21 owing to the aforesaid overtravel provisions, the converging spring 25 being relatively light and just strong enough to assure positive engagement and following-action of the pawl noses into the teeth.

The disclosed construction lends itself to both heavy-working applications and light-duty but high-speed applications for more delicate types of switching or other working applications, yet it is sufficiently simple and rugged to afford reliable operation in both types of application.

I claim:

1. In a high-speed stepping mechanism, a toothed rotatable ratchet wheel, a pair of pawls each drivingly engaging the wheel teeth on opposite sides of the axis of the wheel, a spring attached to both pawls to yieldingly urge the same into said teeth, a solenoid mounted with its bore extending normally of said axis in alignment therewith, a solenoid plunger reciprocable in said bore in between said pawls, a pair of links each having one end pivotally connected to an end region of one of said pawls remote from said wheel, said links each having their opposite and remaining end portions connected to a common pivot point on the outer end of said plunger, each said link having a fixed pivotal mounting at a point in between its connection to a pawl and to said common pivot, a second spring means having connection to the region of pivotal connection of a first one of said links with one of said pawls and urging the said link in a direction to withdraw the plunger from said bore to a normal position, and adjustable stop means positionable to be engaged by the region of pivotal connection of the second one of said links with the corresponding pawl to limit the withdrawal of said plunger to said normal position, reciprocation of the plunger by intermittent energization of the solenoid and action of said second spring means effecting reciprocatory motion of the pawls to step the wheel twice for each reciprocation of the plunger.

2. In a two-step per cycle ratchet stepping mechanism of the known type which includes a rotatable ratchet wheel with a pair of jointly-reciprocable stepping pawls, each of which is located to engage the ratchet teeth on respectively diametric sides of the wheel axis, improvements comprising, to wit: a high-speed pawl means including a solenoid having its bore extending in alignment with, and normally of, the wheel axis; a plunger reciprocable in said bore; a pair of contiguous links extending in opposite lateral directions of said plunger with contiguous ends pivotally connected to an end of said plunger; each said link having an opposite and outer end part pivotally connected to an end of one of said pawls; said links each having a pivot between its ends which is parallel to the wheel axis; spring means drawing the ratchet ends of the pawls respectively toward each other and into said teeth; spring means having connection with said pawl

means to pivotally dispose the contiguous ends of said pawls outwardly of the solenoid bore to withdraw said plunger; means for limiting the reciprocable stroke of said pawl means; and at least one of said pawls having an over-stroke to 5 reduce the loading thereof on the wheel.
